UNITED STATES PATENT OFFICE

154,718

DESIGN FOR A SHOE SHINING MACHINE

William V. Siros, Houston, Tex.

Application May 14, 1948, Serial No. 146,386

Term of patent 14 years

(Cl. D9—2)

To all whom it may concern:

Be it known that I, William V. Siros, a citizen of the United States, residing at Houston, in the county of Harris, in the State of Texas, have invented a new, original, and ornamental Design for a Shoe Shining Machine, of which the following is a specification, reference being had to the accompanying drawings, forming a part thereof.

Figure 1 is a front elevation of a shoe shining machine, showing my new design.

Figure 2 is a side elevational view thereof; and Figure 3 is a top plan view thereof.

I claim:

The ornamental design for a shoe shining machine, as shown.

WILLIAM V. SIROS.
